CLAIM

The ornamental design for an image tracker assembly, as shown and described.

DESCRIPTION

FIG. 1 is an isometric view of an image tracker assembly showing the new design.

FIG. 2 is a left side elevation view thereof.

FIG. 3 is a right side elevation view thereof.

FIG. 4 is a rear elevation view thereof.

FIG. 5 is a front elevation view thereof.

FIG. 6 is a top plan view thereof; and,

FIG. 7 is a bottom plan view thereof.

The broken lines depict portions of the image tracker assembly in which the design is embodied that form no part of the claimed design.
